DOLL

Filed March 14, 1929

UNITED STATES PATENT OFFICE

JOHN H. WILHELM, OF LONG ISLAND, NEW YORK, ASSIGNOR, BY MESNE ASSIGNMENTS, TO MARGON CORPORATION, OF NEW YORK, N. Y., A CORPORATION OF NEW YORK

DOLL

Application filed March 14, 1929. Serial No. 346,831.

This invention relates to a doll, and an object is to provide a doll of the so-called moulded type having a sound producing device appropriately secured in position therein.

5 A more detailed object is to provide simple, efficient and practical means by which a sound producing device may be operatively mounted within a hollow moulded doll body or head.

10 A further detailed object is to provide means to resiliently movably support the sound producing device.

15 A further detailed object is to provide a doll having relatively movable head and limb parts and to provide elastic stringing means for said parts serviceable also as supporting means for the sound producing device.

20 A further detailed object is to so arrange the parts that the elastic stringing means will not only assist in the retention of the sound producing device but will be itself assisted, by the presence of the sound producing device, in its office of holding the head and limbs operatively connected with the body.

25 Other objects and aims of the invention, more or less specific than those referred to above, will be in part obvious and in part 30 pointed out in the course of the following description of the elements, combinations, arrangements of parts and applications of principles constituting the invention; and the scope of protection contemplated will be 35 indicated in the appended claims.

30 In the accompanying drawings which are to be taken as a part of this specification, and in which I have shown merely a preferred form of embodiment of the invention:—

40 Fig. 1 is a transverse sectional view through a doll constructed in accordance with this invention.

45 Fig. 2 is a rear elevational view of the structure seen in Fig. 1, a portion being broken away and shown in vertical section approximately upon the plane of line II—II of Fig. 1.

50 Fig. 3 is a view similar to Fig. 2, though on a smaller scale, and illustrating a modified arrangement of the stringing employed, and

Fig. 4 is a vertical sectional view through a doll head showing the manner in which the sound producing device may be mounted in the head if desired.

Referring to the drawings for describing 55 in detail the structures therein illustrated, it may be first explained that sound producing devices for inclusion in dolls and like toys, although made up in various shapes and sizes, usually consist of a small cylindrical casing, as for instance a short section of cardboard "mailing-tube", closed at its opposite ends by suitable metallic cap pieces at least one of which is perforated so that sound produced by mechanism within the 60 casing may emanate to the outer atmosphere. A sound producing device of this type is accordingly illustrated herein, but it will be understood that the invention is not necessarily restricted to the use of this type of 65 sound producing device.

In mounting a sound producing device within an ordinary stuffed doll body the sound producing device has been readily retained in position by the presence of the 75 stuffing about it, but in a doll body of the moulded type, wherein no stuffing is required or used, other means of retaining the sound producing device has been found necessary.

According to the present invention it is proposed that a moulded doll body may be provided, preferably through its back wall, with a large opening as L of such shape and size as to readily accommodate the sound producing device therethrough.

80 The sound producing device illustrated is indicated generally by the reference character G, consisting of the cylindrical portion 1 and the opposite end cap pieces 2 and 3.

85 Arranged within the opening L is a saddle bracket H. This bracket is preferably made from a strip of sheet metal bent into U-shape. It is arranged almost wholly within the interior of the doll body with its opposite legs 90 as 4 and 5 projecting outwardly through the opening L and being flanged over as at 6 and 7 to lie flat against the outer surface of the body wall 8. The extreme ends are preferably provided with tangs as 9 thereon bent 100

laterally and embedded within the material of the wall so as to rigidly fasten the bracket to said wall.

The size of this bracket is just sufficient to receive the sound producing device, as clearly indicated, the inner end wall surface as 10 of the sound producing device resting against the outwardly facing wall surface 11 of the connecting portion 12 between the two legs 4 and 5 of the bracket, and the outer end surface as 13 of the sound producing device being approximately flush with the outer surface of the body wall 8.

A sheet as 14 of suitable material, such as muslin or cheese cloth, may be pasted onto the outer surface of the sound producing device and onto the adjacent outer surface of the wall 8 for retaining the sound producing device against outward displacement, though it will be understood that any other appropriate means may be employed for this purpose as may be found expedient. The sheet or cloth 14, where it overlies the flanges 6 and 7 of the bracket H, being pasted firmly over said flanges and to the adjacent wall surface portions of the doll body, constitutes an efficient means for assisting the tangs 9 in holding the bracket in rigid connection with the doll body.

The use of a loose woven cloth as a retaining sheet for this purpose has the advantage that it is sufficiently porous to permit the easy migration of sound outwardly therethrough from the sound producing device.

The stringing employed for holding the doll head 15 and the legs 16 movably connected with the body consists of an endless elastic cord as 17. A metallic hook 18 carried by this cord engages an anchor member 19 fixed within the head. The cord extends downwardly from this hook and its lower portion carries a pair of hooks as 20 and 21 which are connected with the anchor members 22 and 23 respectively fixed to the legs 16-16.

In its mid portion the two strands as 24 and 25 of the cord are spread apart and receive the sound producing device G between them.

The bracket H is preferably arranged in a general vertical position within the body, and the strands 24 and 25 of the cord 17, being also in a general vertical position, engage opposite relatively vertical side wall portions as 26 and 27 of the sound device and yieldingly restrain the sound device against lateral movement out of position centrally within the bracket, as will be clearly apparent from the illustration Fig. 2. The bowed or spread condition of the strands 24 and 25 imposes a resilient pressure of substantially equal force against opposite sides of the sound device so that objectionable movement of the sound device within the bracket is unlikely. At the same time the resilient character of this restraining means will always permit a

certain amount of movement of the sound device with respect to the remainder of the doll in the event of severe shocks and this is of advantage since it constitutes a resilient support for the sound device operable to prevent likelihood of injury to the delicate mechanism within the sound device. 70

The bracket H may be of a sufficiently resilient character to permit limited vertical movement of the sound device for the same 75 purpose if desired.

In the modification Fig. 3 the structure is the same in all respects as has been above described but in addition it is proposed by this figure that if desired the opposite strands of the stringing cord 17 may be crossed either above or below the sound device, or in both of these localities, so as to more tightly grip the sound device. In the locality above the sound device the strands, when crossed, may engage hooks 28 and 29 connected with the arms 30 and 31 for holding said arms in operative moveable relation to the body. 80

The modification Fig. 4 illustrates the manner in which the saddle bracket H may 90 be employed for supporting the sound producing device in the head of the doll instead of in the body as in the other Figs. The form, the manner of attaching the bracket, and the use of a cloth sheet covering the 95 sound device and opening L are the same as before, their being only a change of location from the body to the head of the doll. In this event the cloth sheet 14 pasted onto the sound device and onto the surrounding surface of the head is relied upon to retain the sound device against lateral displacement from the bracket H. 100

As many changes could be made in this construction without departing from the 105 scope of the invention, as defined in the following claims, it is intended that all matter contained in the above description, or shown in the accompanying drawings, shall be interpreted as illustrative only and not in a 110 limiting sense.

Having thus described my invention, what I claim as new and desire to secure by Letters Patent is:—

1. The combination with a hollow moulded doll structure having an opening through one wall thereof, a sound producing device arranged interiorly of the structure, of a generally U-shaped metallic bracket arranged interiorly of the structure having its legs projecting outwardly through said opening and turned over upon the outer surface of the structure, the sound producing device being supported between the legs of said bracket with its outer surface in the general plane of the outer surface of the doll structure, means connected with the outer surface of the doll structure overlying said opening in engagement with the outer surface of the sound producing device to hold the sound 115

120

125

130

producing device against displacement from said supporting bracket, and flexible means carried within the structure engaging and pressing against opposite sides of the sound producing device to assist in holding the sound producing device in position in said supporting bracket.

2. A doll having a doll body portion and relatively movable members, a sound producing device arranged within the doll body portion, and resilient supporting means for the sound producing device having connection with said movable members to hold said movable members connected with the body.

15 In testimony whereof I affix my signature.
JOHN H. WILHELM.
